UNITED STATES PATENT OFFICE.

CHARLES STERN, OF JERSEY CITY, AND RICHARD WALLACE BRADEN, OF NEWARK, NEW JERSEY, ASSIGNEES TO B. & S. MANUFACTURING PRODUCTS CORPORATION, OF JERSEY CITY, NEW JERSEY, A CORPORATION OF NEW JERSEY.

LUBRICATOR FOR SHAFTS.

Application filed November 16, 1921. Serial No. 515,635.

To all whom it may concern:

Be it known that we, CHARLES STERN and RICHARD WALLACE BRADEN, citizens of the United States, residing at, respectively, Jersey City and Newark, in the counties of Hudson and Essex, respectively, and State of New Jersey, have invented certain new and useful Improvements in Lubricators for Shafts, of which the following is a specification.

The present invention relates to lubricators, and particularly to a packing and oiling box for shafts and the like.

An object of the present invention is to provide a packing which is adapted to be placed about a shaft and provided with means for directly feeding the oil or lubricant to the shaft without danger of leakage.

Another object of the invention is to provide a device with oil feeding means capable of adjustment into different positions throughout the length or height of a packing box and which are arranged to cooperate with and be held in position by compressible packing elements.

The invention still further aims at the provision of a packing box having a plurality of oil feeders therein for conveying oil from the box directly to the shaft, and also having a compressible packing between the oil feeders and means for compressing the oil feeders and the packing together, and at the same time permitting the free flowing of the oil to the shaft in the desired quantity.

It is a still further aim of this invention to provide means whereby lubricant may be furnished to a shaft which passes into the packing box itself, thereby insuring the lubrication of the shaft; and to provide a packing which is at all times in position to absorb oil from the packing box.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a longitudinal section taken through an oiling box constructed according to the present invention and as applied to a shaft.

Fig. 2 is a transverse section taken through the same on the line 2-2 of Fig. 1.

Fig. 3 is a detail section taken longitudinally through the casing or receptacle of the oiling box.

Fig. 4 is a plan view, partly in section, of one of the oil distributors employed.

Fig. 5 is a transverse section through the same.

Fig. 6 is a longitudinal section through the oiling box, showing a modification in the packing nut; and,

Fig. 7 is a side elevation of an oiling box embodying a modified form of attaching means for the box.

Referring to the drawings, the oiling box 70 comprises a casing or receptacle 10 which is adapted to be placed about a shaft 11 or the like, and which is provided with an inner concentric wall 12 spaced from the outer or main wall of the casing 10 and which provides, between the walls, an annular chamber or receptacle for the reception of a lubricant, such as oil. The receptacle 10 may be provided at any point or points with removable plugs 13 through the openings of 80 which the lubricant may be introduced into the receptacle.

The casing or receptacle 10 may be attached to an adjacent support, such as against the side of a casing, a bearing or the like in any suitable manner. In Fig. 1 the casing 10 is shown as having a radial flange 14 at one end provided with apertures 15 therethrough to receive bolts or the like by means of which the flange 14 may be secured fastened to the support.

In Fig. 7 the casing 10 is shown as provided at its lower end with angularly disposed wrench receiving faces 14^a by means of which the casing may be turned. The casing also has a threaded spud 15^a adapted to be screwed into a correspondingly threaded opening in the support for holding the casing thereto.

The inner wall 12 of the receptacle 10 is 100 shown as provided with spaced apart longitudinal slots or openings 16 extending lengthwise of the receptacle throughout a considerable length thereof, and through which the lubricant in the receptacle is 105 adapted to pass toward the shaft 11. The casing 10 is shown as having an inner closing wall 17 having a reduced axial opening

therethrough for passage of the shaft 11, and the wall 17 is adapted to closely fit the shaft and extends inwardly beyond the wall 12 of the receptacle and provides, between the wall 12 and the shaft 11, a packing chamber, the inner end or bottom of which is formed of the extension of the wall 17. The extension of the wall 17 is shown as formed at its inner side with an outwardly inclined or beveled face 18 forming a packing seat which slopes toward the shaft opening and upon which the packing is adapted to rest.

The other end of the casing 10 is shown as provided with an annular flange 19 projecting from the inner wall 12 and which is spaced about the shaft opening and forms a continuation of the packing chamber. Shown as fitting in the open end of the packing chamber, and within the flange 19 is a compression sleeve 20 having an inner diameter corresponding to that of the shaft opening and adapted to be forced down into the packing chamber by a packing nut 21 which is carried on the flange 19. As shown in Fig. 1, the nut 21 is in the form of a cap which fits over the flange 19 and has screw threaded engagement therewith, and is provided with an angularly faced nut portion 22 on its upper end by means of which the cap 21 may be turned. The upper closed end of the cap extends inwardly beyond the flange 19 and engages the outer end of the compression sleeve 20 for moving the same inwardly when the cap is turned down upon the sleeve 19.

In Fig. 6 a modification of this construction is shown. The compression sleeve 20^a has an internally threaded nut portion 21^a which engages internal flange 19^a. The outer end of the nut portion 21^a is provided with an angular face extension 22^a with which a wrench is adapted to engage for turning the compression sleeve 20^a and the nut portion thereof for feeding the sleeve into the packing chamber.

In both forms of the invention, the compression sleeve, 20 and 20^a, is shown as provided with an inner beveled end 23 which slopes outwardly and toward the shaft opening for cooperation with the packing seat 18 to urge the packing toward the shaft when the parts are assembled.

The packing may comprise a plurality of compressible disks 24 having an internal diameter equal substantially to that of the shaft opening and which are adapted to be placed in superposed relation upon the packing seat 18, and between the latter and the inner end of the compression sleeve 20. When the compression sleeve 20 is advanced inwardly the packing disks are compressed together and the packing is caused to press against the shaft 11. The packing seats or faces 18 and 23 are shown as located sub-

stantially at the opposite ends of the oil slots 16 so as to prevent the escape of oil beyond the opposite ends of the slots and to insure the confining of the oil to the surface of the packing.

The device is provided with one or more oil distributors for directly carrying the oil from the receptacle into contact with the shaft 11. These oil distributors may of course vary in construction, but are shown in the present instance as comprising flat rings 25 of a size to embrace the shaft 11 and having longitudinal slots 26 extending through the walls of the rings for admitting oil therethrough to the shaft. Each ring 25 is shown as provided with a pair of spaced apart outstanding annular flanges 27 projecting from the opposite edge portions of the ring, and which are spaced apart sufficiently to hold the adjacent packing from spreading into the openings 26. The flanges 27 are also of sufficient width to fill, transversely, the packing chamber so as to prevent the packing from being forced about the outer marginal edges of the flanges 27 into the oil spaces therebetween. As shown in Fig. 1, a pair of these oil distributors is used, and it will be understood that as the packing 24 is more or less compressed, these distributors will be correspondingly shifted lengthwise within the packing chamber, and the oil slots 16 are of suitable length to at all times convey the oil from the receptacle to these distributors.

From the above description it is thought that the operation and use of the oiling boxes will be clearly understood, for when the receptacle 10 is placed about the shaft 11, or other suitable device to be lubricated, the packing 24, together with the desired number of distributors, is placed within the packing chamber and the compression sleeve 20 is fitted in the open end of the chamber and forced toward the packing by the packing nut 21. As the packing nut is turned upon the flange 19, the packing 24 is compressed against the inclined faces 18 and 23 and also against the flanges 27 of the oil distributors. The packing is thus caused to press against the inner wall 12 of the receptacle and also against the shaft 11, particularly so since the packing faces 18 and 23 diverge inwardly toward the shaft and thus urge the packing to a greater degree against the shaft. The oil in the receptacle 10 flows through the slots 16 into the oil distributors and is conducted therethrough directly to the shaft to the one or more points desired throughout the length of the packing chamber. The oil is thus uninterrupted in the oil distributors and the wiping action of the packing serves as a means to enable the packing to absorb oil from the shaft, thus aiding in keeping the pack-

ing from drying out. This packing box with its oil distributors has the advantage of directly feeding or distributing oil on the desired points upon the shaft.

5 Of course the casing 10 may be given any suitable construction or form necessary for application to shafts or the like under various conditions, and in the present instance the casing is shown of integral annular construction.

10 It is obvious that various changes and modifications may be made in the details of construction and design of the above specifically described embodiment of this invention without departing from the spirit thereof.

What is claimed is:

1. A lubricator for shafts and the like comprising a casing having a substantially annular chamber for holding a quantity of lubricant and having means for the introduction of lubricant thereto, said casing having an inner tubular wall provided with elongated slots therein, a plurality of small packing rings placed endwise within said tubular wall and surrounding the shaft, and lubricating ring included between said packing rings and having openings communicating with the elongated slots in said inner wall of the casing at one side and directly with the surface of the shaft at the other side whereby fluent lubricant from the chamber is allowed access directly to the surface of the shaft.

35 2. A lubricator for shafts and the like comprising a casing having an inner wall of a tubular character adapted to extend about the shaft and being in spaced relation to the external surface of the shaft, said inner wall having a large number of slots elongated in the direction of the axis of the shaft, said casing having a substantially annular chamber therewithin of the substantial capacity for holding quantity of lubricant about the shaft, a number of relatively small packing rings placed end to end about the shaft and between the shaft and said inner wall of the casing, and a plurality of lubricant rings also of small size and adapted to be fitted between adjacent packing rings at suitable intervals, said lubricant rings having openings therein communicating with the elongated slots in the casing wall and with the outer surface of the shaft.

55 3. A lubricator for shafts and the like comprising a casing having a substantially annular chamber for lubricant adapted to surround the shaft and said casing having an inner tubular wall spaced from the shaft and provided with elongated slots, a number of relatively thin packing rings surrounding the shaft and between the shaft and said slotted casing wall, and lubricant rings of

a similar size adapted to be placed between adjacent packing rings, said lubricant rings having inner walls adapted to fit the external surface of the shaft and provided with circumferentially elongated slots made radially through the rings and opening upon the surface of the shaft within and upon the elongated slots of the casing wall at their outer sides, said rings having flanges extending outwardly substantially flush with the outer edges of the packing rings, and means to compress the packing rings together with the lubricant rings.

4. A lubricator for shafts and the like comprising a casing having an annular chamber for holding the substantial body of fluent lubricant and having means to introduce the lubricant thereto, said casing having an inner cylindrical wall provided with elongated slots extending substantially the length of the lubricant chamber, a beveled seat in the casing inwardly of said inner wall, a plurality of thin packing rings placed about said shaft within said slotted wall and adapted to engage at one end against said beveled seat, a number of lubricant rings placed at intervals between said packing rings and each comprising an annulus having a central opening to fit closely about said shaft and provided with a relatively thin intermediate web having circumferentially elongated slots therein opening directly through the web and about said shaft, and a pair of wide flanges projecting outwardly from opposite ends of the web and extending substantially flush with the outer edges of the packing rings, the inner surface of said flanges being tapered toward the web, a follower having a bevel edge engaging the other end of said series of packing rings, and a nut upon the casing adapted to drive said follower against the rings.

5. A lubricator for shafts and the like comprising a casing adapted to hold a substantial body of the lubricant and extending about the shaft, said casing having an inner slotted wall spaced from the shaft, a series of packing rings extending about the shaft and within said slotted wall, said series of rings embraced substantially within the length of the slots in said wall and communicating by reason of the slots with the lubricant in said chamber whereby to absorb the lubricant, and a lubricant ring included between certain of the packing rings and having openings therein communicating directly with the fluent lubricant in the chamber and with the exterior surface of the shaft.

In testimony whereof we affix our signatures.

CHARLES STERN.

RICHARD WALLACE BRADEN.
